United States Patent Office

Des. 198,287
Patented May 26, 1964

198,287

BOTTLE

Harold D. Hulterstrum, Baraboo, Wis., assignor to Flambeau Plastics Corporation, a corporation of Wisconsin

Filed June 17, 1963, Ser. No. 75,391

Term of patent 14 years

(Cl. D58—5)

FIG. 1.

FIG. 2.

FIG. 3.

FIG. 4.

FIG. 5.

FIG. 6.

The stippled areas represent contrast in surface texture.

I claim:

The ornamental design for a bottle, substantially as shown and described.
